UNITED STATES PATENT OFFICE.

ANTON PAQUET AND ADOLPH PAQUET, OF CHICAGO, ILLINOIS.

COLLAPSIBLE BOX.

1,257,632.

Specification of Letters Patent. Patented Feb. 26, 1918.

Application filed August 21, 1913, Serial No. 785,834. Renewed December 6, 1917. Serial No. 205,891.

To all whom it may concern:

Be it known that we, ANTON PAQUET and ADOLPH PAQUET, citizens of the United States, residing at Chicago, in the county of Cook and State of Illinois, have invented certain new and useful Improvements in Collapsible Boxes, of which the following is a specification.

The essential object of this invention is to provide a collapsible box or container which may be used as a trunk, shipping case, or the like, and the container is so constructed that when collapsed it will occupy the minimum amount of space, but when set up will be practically as strong as if it were non-collapsible.

In the drawings, Figure 1 is a top plan view of the box when in set-up condition, the top cover being opened, however, to permit access to the interior of the box; Fig. 2 is a vertical sectional view on the line 2—2, Fig. 1; Fig. 3 is an end elevation, a detail of the locking arrangement and of the joint between the two parts of the cover being shown in section; Fig. 4 is a section on the line 4—4, Fig. 1, showing the box in collapsed condition; Fig. 5 is a detail in section showing the joint between an end wall and a side wall; Fig. 6 is a detail similar to Fig. 3 of one of the end walls, showing the locking tongue in the position it assumes when the device is to be unlocked or collapsed; Fig. 7 is a section on the line 7—7, Fig. 1; Fig. 8 is a sectional view showing the connection between the bottom and one of the end walls when the box is in open position; and Fig. 9 is a view similar to Fig. 8 showing the parts in the positions respectively assumed by them when the box is collapsed.

The bottom 1 is formed either of a single piece of lumber or other suitable material or a number of pieces rigidly united and secured together so as to form a unitary bottom member. Extending longitudinally of the bottom member 1 are strips 2, which in height correspond to the thickness of the end walls 3. Said strips 2 are permanently secured to the bottom 1 by suitable fastening devices, such as screws 4, and by reinforcing angle-irons 5 and corner plates 6.

Hinged to each strip 2 by hinges 7 is a side member 8, the hinges 7 being so formed as to permit the side members 8 to fall inwardly when the box is collapsed. As best shown in Figs. 2 and 4, strips 2 and sides 8

are each provided with beveled edges 9 and the pintles of the hinges 7 are received within the space which is formed by beveling the edges at 9. The strips 2 and sides 8 may be countersunk at 10 so as to receive the hinges 7 in such manner that when the box is set up the outer or exposed surfaces of the hinges 7 will be flush with the surfaces of the strips 2 and sides 8.

The end members 3 are each preferably formed of an end wall 11 which is reinforced by the exterior reinforcing strips 12, which exterior reinforcing strips are provided both to improve the appearance of the box as well as to strengthen the ends, and the exterior reinforcing strips 12 have their edges 13 suitably beveled. As best shown in Figs. 2 and 8, each end wall 11 is secured to the bottom 1 by hinges 14 and is adapted to fall inwardly upon said hinges. The strip 12 which extends parallel to the bottom projects beyond the edge of the end 11, and to the bottom 1 a piece of beading or quarter-round 15 is secured by screws 16, which said quarterround 15 neatly fills the space between the members 11 and 12 and thus forms a perfectly tight joint between the bottom and the end of the box when the box is in open position as shown in Fig. 8. The member 15 is mortised or cut out at 17 to receive that leaf of the hinge 14 which is fastened to the end 11.

The top of the box is formed of two members 18 and 19 which are, respectively, secured to the sides 8. Each side 8 carries a leaf 20 terminating in a loop 21, and a similar leaf 22 and loop 23 are borne upon each of the members 18 and 19. The U-shaped staple-like pintles 24, pass through the loops 21 and 23, and in this manner the top members 18 and 19 are hinged to the ends 8, there being sufficient freedom of movement, however, to permit said members 18 and 19 to lie in planes parallel to the members 8 as shown in Figs. 1 and 4, or to extend perpendicularly to said members 8, as shown in Fig. 2.

When the members 18 and 19 comprising the top are folded inwardly, as shown in Figs. 2 and 3, they will close the receptacle, resting upon the upper edges of the ends 11 at such times. The members 18 and 19 are provided with a coöperating tongue 25 and groove 26 so as to form a perfectly tight joint when the box is set up, as shown in Fig. 2.

Fig. 2, which joint, moreover, will be concealed or protected by the flange 27 secured to the member 19. Upon the under side of the member 19 near each end there is a recess or notch 29 formed by the flange 30, best shown in Figs. 3 and 6. When the right end 31 of the sliding tongue 32 is forced in a direction inwardly from the position shown in Fig. 3, said end 31 will be received with 10 in the recess 29, and thus the member 19 will be locked in the position shown in Figs. 2, 3, and 6. When the member 19 is thus locked, the flange 27, which is carried upon said member, co-operates with the member 18 and holds that member also against movement. The sliding tongue 32 is received within a countersink 33, which is near the upper edge of each member 11, and plates 34, secured in place by screws 35, guide said 20 tongue and retain the same in place, permitting the tongue to slide from the position of Fig. 6 to that of Fig. 3 and back again, it being obvious that when the sliding tongue 32 is in the position of Fig. 3, the 25 container will be locked in set-up position, whereas, when the same member is in the position of Fig. 6, the cover may be opened and the device collapsed. That end 31 of the locking tongue which is received within 30 the recess 29 is preferably bent at right angles to that part of the same member which is received within the countersink 33. The sliding tongue 32 is provided with a loop 35^a which projects through a recess 36 cut in the end wall 11. To slide the tongue 32 from one position to the other, the operator grasps the loop 35^a, which serves as a knob or handle, and moves the tongue 32 back or forth in either direction desired. 35 40 The strip 27 and top member 18 are provided with registering perforations 37 and 38, and the end wall 11 is perforated at 39, the perforations 39 being adapted to register with the perforations 37 and 38 when the 45 device is set up; and when the container is set up and the locking tongue moved to the position of Fig. 3, a wire 40 can be passed through perforations 37 and 39 and through the perforation 41 in the loop 35^a. If the 50 ends of this wire be brought together by a seal 42, the container when once set up and locked will so remain until the seal be broken.

Each of the end walls 11 is provided with 55 a recess 43, and within said recess the U-shaped clamp 44 is secured, said clamp being adapted to lock or co-operate with a similar clamp 45 fastened to the side 8, as best shown in Fig. 5. This construction prevents the 60 end wall from moving outwardly beyond the vertical position, though permitting same to fall inwardly when it is desired to collapse the structure.

From the foregoing detailed description 65 of parts, it will be clearly evident how the

container is to be set up or collapsed, but assuming that the structure is collapsed and the parts are in the positions respectively shown for them in Fig. 4, the members 8 are swung upon their hinges until said members 70 8 are in vertical position, resting upon the strips 2, as shown in Fig. 2. The ends 11 are then swung upon their hinges until said members 11 also stand in vertical position, being prevented from moving too far by 75 locking means 44 and 45. The top members 18 and 19 which comprise the cover are then swung upon the hinges 21 and 23 until the cover members assume the horizontal position of Figs. 2 and 3. Then the locking 80 tongues 32 may be pushed toward the right, Fig. 3, or toward the left, Fig. 2, and said tongues 32 will lock the container in set-up position, for when the tongues 32 are in the position of Fig. 3, the top member 19 will 85 be locked against upward movement, the holding of the member 19 in place will, because of the flange 27, keep the member 18 from being lifted up, and the tongues 32 themselves, by locking the ends 11 to the 90 cover member 19, will prevent the ends 11 from falling inwardly.

As previously stated, the strips 2 are of a height corresponding to the thickness of the ends 11. The term "corresponding" does 95 not mean exactly equal, because, as shown in Fig. 4, the upper edge of the strip 2 is a little higher than the top edge of the strip 12; but the member 2 is of such a height that the side walls 8 when collapsed will lie 100 perfectly flat. The axial line of the pintle of the hinge 7 should be in the same plane as the upper edge of the strip 2, and since these pintles are placed in the recesses formed by the beveled edges 9, it follows 105 that the lower surfaces of the sides 8, when said members are folded as shown in Fig. 4, will be a little lower than the top edges of the strip 2, which strips, therefore, must be of the height necessary to permit said under 110 surfaces of the side walls 8 to rest directly upon the strips 12.

We do not limit ourselves to the precise form of container depicted in the drawings, but numerous changes in the details of construction may be made without departing 115 from the scope of the invention.

We claim as our invention:

1. A folding box comprising a bottom member, narrow strips permanently secured 120 to the side margins of the bottom and projecting upwardly therefrom, end members hinged to the ends of the bottom and adapted to be folded inwardly upon the bottom, side members hinged to the side strips 125 and adapted to be folded inwardly upon the end members, cover members hinged to the side members and adapted to be folded outwardly upon the side members, said end members being elevated slightly above the 130

bottom when in open position to leave intervening spaces, strips of beading secured to the bottom and located in said spaces, and reinforcing strips secured to the exterior of the end members and having their lower portions projecting below said end members and adapted to abut against the bottom when the box is open.

2. A folding box comprising a bottom member, narrow strips permanently secured to the side margins of the bottom and projecting upwardly therefrom, end members hinged to the ends of the bottom and adapted to be folded inwardly upon the bottom, side members being hinged to the side strips and adapted to be folded inwardly upon the end members, cover members hinged to the side members and adapted to be folded outwardly upon the side members, said end members being elevated slightly

above the bottom when in open position to leave intervening spaces, strips of beading secured to the bottom and located in said spaces, said beading strips being quarter round to permit the end members to turn 25 on their hinges, and reinforcing strips secured to the exterior of the end members and having their lower portions projecting below said end members and adapted to abut against the bottom when the box is 30 open.

In testimony whereof we hereunto affix our signatures in the presence of two witnesses.
